Design for Frame for Pictures

Dec. 430

Edmund L. Freeman, of Bellville, N. Y.
Letters Patent No. 430—Dated Decr. 25th 1851.

The schedule referred to in these Letters Patent and margin of same
To all whom it may concern.

Be it known.

that I, Edmund L. Freeman, of Bellville in the county of Jefferson, and State of New York have invented a new and ornamental design for a frame for a Cheese Pull. And I, hereby declare the following to be a true and full description thereof, reference being had to the drawings, hereto annexed which drawings constitute a part of said description; as follows:

The plan, as will be seen, by referring to the drawing is composed of first, two triangular pilasters A A fluted (or rued) across diagonally, with capital C.C, ornamented with leaves and a fringe B fluted in a similar form, with the pilasters and a raised tablet (or panel) E in the centre. There are

surmounted with a top frame E supported by brackets GG in a scroll form, ornamented with leaves, and fluted on the inner face. I do not confine the use of my frame to the pup but it may also be used for a mantle piece.

What I claim, at this and desire to secure by letter patent is the design of the frame for presses, mantle pieces &c above described.

In confirmation whereof I hereto subscribe my name in presence of two witnesses
